UNITED STATES PATENT OFFICE.

MICHAEL POTOLOWSKY, OF MOSCOW, RUSSIA.

METHOD OF TREATING MARINE-ANIMAL OILS.

No. 823,361.

Specification of Letters Patent.

Patented June 12, 1906.

Application filed January 27, 1902. Serial No. 91,514.

To all whom it may concern:

Be it known that I, MICHAEL POTOLOWSKY, a subject of the Emperor of Russia, residing at Moscow, Russia, have invented a certain 5 new and useful Method of Treating Marine-Animal Oils; and I do hereby declare the following to be a full, clear, and exact description of the invention, such as will enable others skilled in the art to which it appertains to make and use the same.

My invention relates to a new method of treating marine-animal oils. It is well known that such marine-animal oils consist principally of glycerids of the liquid fatty 15 acids (up to eighty-five per cent.) and owing to the insignificant proportion of the glycerids of the solid fatty acids contained in such marine-animal oils have been employed almost exclusively for the manufacture of 20 soft soap only, not being capable of use for ordinary hard soap and candles owing to their strong disagreeable smell, which it has been impossible hitherto to remove.

It is the object of my invention to remove 25 this disagreeable odor from marine-animal oils and at the same time to produce a new product which owing to its resemblance to tallow may well be designated as "marine-animal-oil tallow."

30 In carrying out my process and in obtaining my new product I preferably proceed in the manner hereinafter pointed out in connection with the accompanying drawings, which show an apparatus suitable for the 35 performance of my process.

In the drawings, Figure 1 is a vertical section of the apparatus; and, Fig. 2 a plan view of the same, partly in section.

Referring to the drawings, *a* is a tank or 40 reservoir located within a casing *a'*, a space *i* being left between the two, as shown in Fig. 1. The tank *a* is provided with a lid *b*, having a manhole covered by a manhole-plate *c*. Through the manhole the marine-animal oil 45 to be treated may be poured into the tank. An acid-supply pipe *d* enters the tank through its cover, being provided inside with a series of small holes. Through this pipe sulfuric acid may be sprayed into the marine-animal 50 oil. Blades *e* are provided within the tank for the purpose of stirring the mixture, which blades are rotated by means of a vertical shaft *f*, having arms *f'*, from which the blades are carried. The shaft *f* is stepped at 55 the bottom of the tank and projects through the cover *b*, the projecting end being pro-

vided with a bevel gear-wheel *g*, arranged to engage a corresponding bevel gear-wheel *g'*, fixed to a power-shaft *g*, as shown, which is to be rotated by any suitable means when it 60 is desired to operate the stirrer.

The space *i* between the tank *a* and its casing *a'* may be supplied with a cooling liquid, such as water, through the water-inlet pipe *h*, provided with a valve *h'* for controlling the flow of water to the space *i*. A branch pipe *k*, leading from the pipe *h* to the interior of the tank *a*, serves to supply water to the latter for a purpose hereinafter explained. The pipe *k* is controlled by a valve *k'*, and in the pipe *h* beyond the valve *k'* is provided another valve *h''*, whereby the water to both the space *i* and the interior of the tank *a* may be controlled simultaneously. In order to remove the water from the tank *a*, a 70 water-outlet valve *l* is arranged at the bottom of the tank. Near the bottom and within the tank *a* is arranged a spiral coil *n*, provided with a plurality of holes, whereby steam may be admitted to the tank, the said 75 coil *n* being supplied with steam through a pipe *m*, controlled by a cock *m'* from a steam-pipe *p*, which also admits steam to the space *i* through a cock *p'*, an additional cock *p''* being provided in the pipe *p* outside its connection with the pipe *m*. The space *i* may be emptied by an outlet-cock *o*. The contents of the tank *a* may be emptied through a large outlet-valve *q* at its bottom.

In carrying out my improved process with 90 the above apparatus I preferably proceed as follows: The marine-animal oil to be acted upon is supplied to the tank through the man-hole, whose plate *c* is then secured in place. Then twenty to twenty-five per cent. of sulfuric acid of 1.84 specific gravity is added to the marine-animal oil through the pipe *d* and sprayer *d'*, the oil being stirred continuously by the stirring-blades *e*. Finely-ground nitrates are then added through the manhole in 95 such a quantity that the amount of free nitrous acid will be substantially five per cent. of the oil which is being treated. In order to regulate the temperature of the oil according to its quality, cold water may be supplied to the space *i* through the pipe *h*, it being preferable with this process to maintain the temperature somewhat below 60° centigrade, and preferably not exceeding 40° to 50° centigrade. The stirring is continued until 100 the reaction has terminated, which requires usually several hours. Thereafter the stir- 105 110

ring-blades *e* are stopped, and water of suitable temperature is supplied to the tank *a* through the pipe *k* simply in order to remove any surplus sulfuric and nitrous acids, the wash-water being let off through the valve *l*. In order to remove any sulfo fatty acids which may still remain in the tallow, steam is supplied to the tank through the coil *n*, whereupon the tallow may be again washed, if necessary, by supplying more water through the pipe *k* and drawing it from the tank through the outlet *l*. In order to free the solid tallow, which is now odorless, from any remaining water, the space *i* may be emptied of its water by opening the valve *o*, and steam may be admitted to said space through the steam-pipe *p*, the heat of the steam rapidly evaporating the said remaining water. As soon as this is done the tallow may be run through the tank by opening the outlet-valve *q*. The effect of the sulfuric acid on this process consists, on the one hand, in converting the glycerids of the marine-animal oil into glycerin and free fatty acids and, on the other hand, in changing the oleic acid into sulfo-oxy-stearic acid, which latter on being further treated with steam is converted into sulfuric acid and oxystearic acid. The nitrous acid produced by the effect of the sulfuric acid on the nitrites changes the oleic acid into solid elaidic acid, $(C_{18}H_{34}O_2)$ at the same time completely decomposing, through the effect of the acids, the strong-smelling parts of the marine-animal oil, which consists chiefly of tertiary amines.

By the common and simultaneous treatment of the marine-animal oil with sulfuric and nitrous acid not only the maximum quantity of liquid fatty acids contained there in is converted into solid fatty acids, but also the strong repulsive smell is completely removed, while anhydrous substances are also formed which present a characteristic feature of the new product. These anhydrous substances or anhydrides are by-products formed by the action of sulfuric acid upon the oleic acid of the marine-animal oils and consist principally of anhydrid of oxystearic acid and anhydrid of oleic acid.

If it is desired to treat marine-animal oils with sulfuric acid only, similar results may be obtained by omitting the step consisting in the addition of the ground nitrites described above and maintaining the temperature above 50° centigrade and preferably slightly above 60° centigrade, sulfuric acid of 66° Baumé being added in a quantity such as to be at least twenty-five per cent. of the oil which is being treated. The product resulting from this treatment with sulfuric acid only is also without smell, although the production of solid acids is less than on simultaneously treating with the two acids at the lower temperature.

The transformation of the strong-smelling

amines of the marine-animal oils into odorless salts by means of sulfuric acid and nitrous acid is to be seen by the following reactions:

I. Sulfuric acid:

II. Nitrous acid:

The odorless salts thus obtained being dissolved in water are removed by washing.

The treatment of marine-animal oils with two as well as with one acid under the conditions stated above can of course be carried out on all kinds of such oils, consequently on such as are obtained from fish, seal, and whales. The product thus obtained, which may be called "marine-animal-oil tallow," has the appearance of ordinary tallow and is without smell. However, the ingredients of such tallow differ from those of the ordinary tallow in the fact that the former does not consist of glycerids of the free fatty acids, but of free fatty acids themselves—that is to say, to the extent of sixty to seventy per cent. of solid, twenty to thirty per cent. of liquid fatty acids, and ten per cent. of anhydrous substances, which latter substances enable the new product to be used as a greasing or lubricating material.

In the manufacture of hard soap and candles the new product completely replaces the ordinary tallow and has the further advantage of not becoming rancid. By reason of the properties of the new product—viz., its consistency, increased standard of solid fatty acids, and absence of smell—it is adapted for use in many industries.

What I claim, and desire to protect by Letters Patent, is—

1. The process of purifying marine-animal oils which consists in converting the strong-smelling amines into soluble salts and removing the salts.

2. The process of purifying marine-animal oils which consists in subjecting the oils to the action of nitrous acid and a mineral acid, and washing the product.

3. The process of treating marine-animal oil, which consists in converting the strong-smelling amines of such an oil into odorless salts and then removing said odorless salts.

4. The process of treating marine-animal oils, which consists in acting upon such an oil with sulfuric and nitrous acids to convert the strong-smelling amines into odorless salts, and then removing said odorless salts.

5. The process of treating marine-animal oils, which consists in acting upon such an oil with sulfuric and nitrous acids and afterward treating the resultant product with steam.
- 5 6. The process of treating marine-animal oils, which consists in acting upon such an oil with sulfuric and nitrous acids at a temperature not above 60° centigrade, and afterward treating the resultant product with steam.
- 10 7. The process of treating marine-animal oils, which consists in acting upon such an oil with sulfuric and nitrous acids, afterward treating the resultant product with steam and then washing said product.
- 15 8. The process of treating marine-animal oils, which consists in acting upon such an oil with sulfuric and nitrous acids, then washing the resultant product, then submitting it to the action of steam, again washing it, and
- 20 finally evaporating off any moisture remaining.
9. The process of treating marine-animal oils, which consists in adding sulfuric acid and nitrites to such an oil, stirring the mixture, washing it and then treating it with steam.
- 10 10. The process of treating marine-animal oils, which consists in adding sulfuric acid and nitrites to such an oil, maintaining the
- 25 mixture at a temperature above 50° centigrade while stirring it and afterward acting upon the mixture with steam.
- 30 11. The process of treating marine-animal oils, which consists in adding sulfuric acid and nitrites to such an oil, maintaining the mixture at a temperature above 50° centigrade and stirring it, then washing it, and then submitting it to the action of steam.
- 35 12. The process of treating marine-animal oils, which consists in adding sulfuric acid and nitrites to such an oil, maintaining the mixture at a temperature above 50° centigrade, stirring it for several hours, then washing it, then submitting it to the action of steam, again washing it and finally evaporating off any moisture remaining.
- 40 13. The process of treating marine-animal oils, which consists in adding twenty to twenty-five per cent. of sulfuric acid to such an oil, adding ground nitrites in sufficient quantity to produce substantially five per cent. of free nitrous acid, maintaining the temperature below 60° centigrade, stirring the mixture, then washing the resultant product, then submitting it to the action of steam and finally again washing it.
- 45 14. The new product, marine-animal-oil tallow, consisting of sixty to seventy per cent. of solid fatty acids, twenty to thirty per cent. of liquid fatty acids and ten per cent. of anhydrous substances.
- 50 In testimony whereof I affix my signature in presence of two witnesses.
- MICHAEL POTOLOWSKY.
